ABSTRACT

A bucket for an earth-moving machine made of aluminium alloy and having a cutting edge assembly fabricated from steel, enclosing the forward edge of the bottom of the bucket.

FIG. 1.

FIG. 2.

FIG. 3.

FIG. 4.

BUCKET FOR EARTH MOVING MACHINES

This invention relates to buckets for earth-moving machines such as frontend loaders, and has as its principal object the provision of a lightweight bucket.

On large earth-moving equipment, it is necessary to use robust construction to withstand the adverse conditions under which the machines normally operate, such as on construction sites. Nevertheless, it is desirable to maintain the unladen weight of the vehicle to a minimum in order that the machine may have a maximum payload capacity. Although lightweight material, such as aluminium alloys, are now available having sufficient tensile strength for use in such buckets, these materials do not possess the necessary wear resistance.

With the above stated principal object in view, there is provided according to the present invention an earth-moving machine bucket comprising a bottom, back and sides fabricated from aluminium alloy plate material, and a cutting edge assembly fabricated from steel plate material secured to the bucket bottom to enclose the forward edge of the bucket bottom.

Preferably, a cutting edge assembly, also fabricated from steel, is provided to enclose the forward edge of each side of the bucket, at least along the lower portion thereof.

Conveniently, the cutting edge assembly comprises a cutting member adapted to abut the underside of the bucket bottom along the front marginal edge portion, and to project forwardly therefrom, and a clamp plate to abut the top face of the front marginal edge of the bucket and to engage the cutting member at a location spaced forwardly of the front edge of the bucket. Attachment bolts pass through the cutting member and clamp member so that, upon tightening of the bolts, the front marginal portion of the bucket bottom is securely clamped between these members. Preferably, after the attachment bolts have been tightened, the clamp member is welded to the cutting member along the line of their engagement, spaced forwardly from the front edge of the bucket bottom. This construction provides maximum strength for supporting vertical loads caused by the bucket breaking-out heavy material from the work face. The cutting edge assemblies on the sides of the bucket may be of a similar construction and a reinforcing gusset may be welded to the side and bottom clamp members in the area of the junction of the side and the bottom of the bucket.

Appropriate mounting brackets or plates are secured to the back of the bucket for attachment of the bucket to the support and lifting mechanism of the machine. These mounting brackets and plates are also fabricated from aluminium alloy plate material.

In the previously used all-steel bucket, the ratio of bucket weight to payload weight was normally of the order of 4:1 with a large bucket handling light or low density materials. The bucket in accordance with the present invention, which is principally fabricated from aluminium alloy, can result in a saving of approximately 50 percent of the bucket weight, and thus may result in an increase of approximately 12 percent in the payload capacity.

The invention will be more readily understood from the following description of one practical arrangement of a bucket suitable for use on a frontend loader and as illustrated in the accompanying drawings.

In the drawings:

FIG. 1 is a side elevation of the complete bucket;

FIG. 2 is the partial plan view of the bucket shown in FIG. 1;

FIG. 3 is a sectional view along line 3—3 in FIG. 2;

FIG. 4 is a sectional view along line 4—4 in FIG. 1.

Referring now to the drawings, the bucket is of general conventional construction having end plates 6, a bottom 7, and back 8. Brackets 10 and 11 are secured to the back 8, and incorporate apertures 12 and 13 to receive pins for attachment of the bucket to the boom of a frontend loader. The bottom 7, and back 8, are each formed from two superimposed sheets of aluminium alloy plate 15 and 16, which aluminium alloy may, for example, be one of those listed in Table 3 on page 593 of Mark's Handbook, Fifth Edition (1951). Likewise, the end plates 6 are made of aluminium alloy plate and are welded to the plates 15 and 16 which form the bottom and back of the bucket. Each end plate 6 is provided with two stiffener strips 20 and 21 which are welded to the outer surface of the end plate and extend in a direction generally parallel to the front edge of the the bucket and plate.

Referring now to FIG. 3, the forward cutting edge assembly attached to the forward marginal portion of the bottom 7 of the bucket, comprises a cutting member 25, a clamp plate 26, a backing strip 27 and a thrust strip 28. The cutting member is made from a high carbon steel to provide a maximum resistance to wear, and includes a mounting portion 30 and a cutting edge portion 31. The clamp member 26 has a turned-down front edge 38 so that, when the cutting member and clamp member are assembled to the bottom of the bucket, the turned-down portion forms a continuation of the inclined upper face 39 of the cutting edge portion. The backing strip 27 is welded to the rear of the mounting portion of the cutting member, prior to assembly to the bucket, to provide a greater effective length to the mounting portion at a reduced cost as the backing strip 27 may be made from mild steel.

The thrust strip 28 is positioned between the shoulder 35 formed at the junction of the cutting edge and mounting portions of the cutting member, and the forward edge of the bottom of the bucket. The thrust strip is also made from mild steel. The cutting edge assembly is secured to the forward marginal portion of the bucket by two rows of bolts 40, one row passing through the mounting portion 30 of the cutting member and the clamp member 26 and the other row passing through the backing strip 27 and the clamp member 26. Upon tightening these bolts, the forward marginal portion of the bucket bottom is gripped between the clamp member and the cutting member and backing strip to provide a secure attachment of the cutting edge assembly to the bottom of the bucket. In operation, the forward portion of the bottom of the bucket made of relatively soft aluminium alloy is protected from contact with the earth or other material being handled by the bucket and is thus protected from wear. The cutting of the earth is effected by the cutting assembly which is made of steel and consequently can resist the abrasive action of the earth and resultant wear.

The front edge of each of the end plates of the bucket are also protected along the majority of their length by a side cutting edge assembly of somewhat simpler construction as shown in FIG. 4. This assembly comprises a flat cutter member 45 and a clamp member 46 which engage the outer and inner face respectively of the end plate along the front marginal edge and are clamped

thereto by a row of bolts 47. If desired, the clamp member 46 may be welded to the cutter member 45 along the line of contact therebetween spaced forwardly from the edge of the bucket side as indicated at 48. Similarly, the clamp member 26 and cutter member 25 may be welded as indicated at 29. These two welds are made after the respective members have been secured in position by tightening of the attachment bolts.

I claim:

1. An earth moving bucket comprising:
a generally U-shaped member forming the bottom and back for said bucket;
said U-shaped member consisting of a pair of complementary formed sheets of aluminum alloy plate material;
an end member secured to each of the opposite ends of the U-shaped member;
each of said end members formed of a single sheet of aluminum alloy plate material and having a free edge;
stiffeners secured to the outer surface of each of said end members and extending substantially parallel to said free edges;
a cutting member formed of steel material including a mounting portion and a cutting edge portion, said cutting edge portion forming a shoulder with said mounting portion;
a thrust strip formed of steel material positioned between said shoulder and the outer one of said pair of sheets with said cutting member positioned against the bottom of the bucket;
a clamping member formed of steel material, having

- a turned-down position substantially contiguous with said cutting edge portion, positioned adjacent the inner one of said pair of sheets;
- a plurality of first fastening members extending through the mounting portion, the pair of sheets and the clamping member for clamping the pair of sheets between said clamping member and said mounting portion; and
first weld means securing said turned-down portion to said cutting edge portion.
2. An earth moving bucket according to claim 1 and further comprising:
a backing strip formed of steel material secured to the free end of said mounting portion; and
a plurality of second fastening means extending through said backing strip, said pair of sheets and said clamping member.
3. An earth moving bucket according to claim 2 and further comprising:
a cutter member positioned adjacent to each of the free edges of said end members;
a clamp member positioned adjacent to each of said cutter member on the opposite end of said end members;
each clamp member having an angled portion approaching said cutter member;
a plurality of third fastening means extending through said cutter members, said end member and said clamp members; and
second weld means securing said angled portion to said cutter member.
